UNITED STATES PATENT OFFICE.

ADOLPH WAHLE, OF DAVENPORT, IOWA.

MECHANICAL MOVEMENT.

SPECIFICATION forming part of Letters Patent No. 759,648, dated May 10, 1904.

Application filed July 10, 1901. Serial No. 67,745. (No model.)

To all whom it may concern:

Be it known that I, ADOLPH WAHLE, a citizen of the United States, and a resident of Davenport, in the county of Scott and State 5 of Iowa, have invented certain new and useful Improvements in Mechanical Movements, of which the following is a full, clear, and exact specification.

My invention relates to mechanical movements for converting a continuous rotary movement into a reciprocating rotary movement for use in a variety of machines, such as churns, washing-machines, or the like.

My invention consists in the matters hereinafter set forth, and more particularly pointed out in the claims.

In the drawings, Figure 1 is a view in side elevation of my invention, illustrating its application to a washing-machine, the upper portion only of the latter being shown and this in section. Fig. 2 is a view in side elevation of the translating devices, the remainder of the mechanism being removed, the point of view being opposite to that of Fig. 1. Fig. 3 is a 25 view in end elevation of the parts shown in Fig. 2.

Referring to the drawings, a drive-wheel A is shown as journaled on a stud projecting from one end of a main supporting-frame B 30 and as communicating its continuous rotary motion to a drive-shaft F through the medium of a pinion D, secured concentrically to the hub of the drive-wheel, and a gear E on the adjacent end of said drive-shaft in mesh with 35 said pinion. If desired, the drive-wheel can be secured directly to the end of the drive-shaft, its connection therewith, as shown in the drawings, being simply for the purpose of increasing the power transmitted to the 40 drive-shaft. Said drive-shaft F is revolvably secured in bearings b b' on the frame B, and at its end portion remote from the gear E, which projects through and beyond the bearing b', it is provided with an angular deflection f', which forms an offset or bend, the return leg or stretch of which, hereinafter designated as the "angular extension" f', is in a 45 plane oblique to the axis of the shaft F, which latter intersects it, preferably at its center of 50 length. As a consequence of the obliquity of

position of the angular extension f' the rotation of the main shaft of the shaft F causes the angular extension to describe by its movement a double cone, and a section taken on a plane of the axis of the straight portion of 55 the shaft F through the path of motion of said angular extension shows an angular oscillatory motion of said extension. The purpose of my invention is to convert this angular movement of the extension into an oscillatory reciprocating motion, eliminating the effect of the rotary motion of the extension around the shaft-axis. To this end I secure on 60 said extension f' a sleeve J in such a manner as to revolve freely thereon, while at the same 65 time preventing longitudinal displacement thereof. As a convenient means of effecting this a feather-pin j is employed, which is secured to and projects radially from said angular extension into an annular groove or key- 70 way j', which is formed on the interior surface of the sleeve and for a portion of its circumference extends entirely through the wall of the sleeve in order to form a slot through which the pin may be inserted when the sleeve 75 is positioned on the extension. Obviously, however, any other well-known mechanical device may be employed to secure the sleeve J against longitudinal displacement.

Projecting from sleeve J, at an angle of 80 about ninety degrees to the plane of its pivotal contact with extension f', is an arm K, which extends sidewise and then downward in a transverse plane striking through the point where the axes of the straight portion of shaft 85 and of said extension intersect. The end portion of said arm K farthest from sleeve J is preferably cylindrical and is journaled in a plane at right angles to the axis of said sleeve in a pivotal socket formed in the web of a segmental rack L. The segmental edge of rack 90 L extends beyond the teeth of said rack and is seated and has a sliding peripheral movement in the correspondingly-curved runway b⁴ of the track b⁵, which latter is integral with 95 the base-plate of the supporting-frame B and arranged in a plane parallel with the axis of the drive-shaft F. The motion imparted to the segmental rack by the angular extension f' through the medium of arm K causes it to os- 100

cillate in said runway b^4 , and the center of oscillation of said segmental rack is in a line perpendicular to the plane of the axes of the shaft and angular extension at their point of intersection or the center of oscillation of said angular extension. In order to allow perfect freedom of motion between said arm K and the rack L, I adapt the outer portion k of the arm K to have rotating engagement in said 5 socket, thereby effectually providing for unequal wear or accidental distortion. To convert this oscillating reciprocal motion of the circular rack L into a reciprocating motion, I mesh therewith a gear H, which is secured, 10 as illustrated in the drawings, on a shaft G, which latter is revolvably secured in bearings b^2 and b^3 on the main frame B. As shown in the drawings, said shaft G is mounted at right angles to the drive-shaft F; but it is obvious 15 that it may be secured at any angle to the shaft F, so long as it lies in a plane permitting proper engagement of the gear H and rack L.

The operation of the mechanism as a whole is obvious. A continuous rotary motion is 20 imparted by the driving-wheel A to the driving-shaft F. The movement of the latter causes the rotation of the angular extension and at the same time an angular or rocking motion of the latter on its center of oscillation, which latter, as before stated, corresponds to the intersection of the axes of the two parts of the shaft. Said angular or rocking movement is communicated to the sleeve J and its projecting arm K, and these in turn 25 impart an oscillatory motion to the curved rack L. The latter therefore is caused to move reciprocally in its runway, and so imparts a reciprocal rotary motion to the gear H and the shaft G.

There is an absence of the usually employed gears and resultant decrease in loss of power by friction, while it is evident that the parts may be constructed and assembled very easily.

I claim as my invention—

1. A device for the purposes stated comprising a continuously-rotating shaft, a portion of said shaft being bent at an angle oblique to the main portion of the shaft, an oscillating 50 curved rack, having a socket extending radially from the inner edge thereof, a sleeve rotatively secured on said oblique portion of the shaft, an arm extending from said sleeve having rotative engagement with said socket, 55 and a reciprocating rotary shaft actuated by said rack.

2. A device for the purpose as stated, comprising a continuously-revolving main shaft, having a crank whose axis is oblique thereto 60 and is intersected by the axis of said shaft at a point mediate its ends, a segmental gear adapted to oscillate in a vertical plane parallel to the main shaft, the axis of said segmental gear passing through the point of intersection

of the axes of said shaft and crank, a pinion 65 adapted to mesh with said gear, a sleeve rotatively secured on said crank, an arm secured to and projecting from said sleeve the axis of said sleeve being at the point of intersection of the axes of said shaft and crank, said arm 70 having rotative engagement in a radially-extending socket of said segmental gear.

3. A device for the purposes stated, comprising a continuously-revolving main shaft having a crank whose axis is oblique thereto and 75 is intersected by the axis of said shaft at a point mediate its ends, a segmental gear adapted to oscillate in a vertical plane parallel to the main shaft, the axis of said segmental gear passing through the point of intersection of 80 the axes of said shaft and crank, a rotary reciprocating pinion the transverse plane of the perpendicular axis of which intersects the point of intersection of the axes of said shaft and crank and is engaged by said gear, a sleeve 85 rotatively secured on said crank, an arm secured to and projecting from said sleeve the axis of said sleeve being at the point of intersection of the axes of said shaft and crank, said arm having rotative engagement in a radially-extending socket of said segmental gear.

4. A device for the purposes stated comprising a continuously-revolving main shaft, having an integral crank formed by a return-off-set therein extending at an oblique angle to said shaft, the axes of which and said shaft intersect at a point mediate the ends of the crank, a segmental gear adapted to oscillate in a vertical plane parallel to the main-shaft 95 axis, the axis of said segmental gear passing through the point of intersection of the axes of said shaft and crank, and which oscillates perpendicular to the plane of said shaft, a rotary reciprocatory pinion adapted to mesh 100 with said segmental gear, and means carried by said crank and engaging said gear in planes transverse to each other for transmitting the angular movement of said crank to said gear.

5. A device for the purposes stated, comprising a main frame, a continuously-revolving main shaft having a crank the axis of which is oblique to the axis of said shaft and is intersected by the latter at a point mediate its ends, a segmental gear oscillating in a vertical plane parallel to the main shaft, the axis of said segmental gear passing through the point of intersection of the axes of said shaft and crank, a rotary reciprocatory pinion adapted to mesh with said gear, means on said frame 110 to movably retain said gear in mesh with said pinion, and means engaging said gear in planes transverse to each other and transmitting the angular movement of said crank to said gear.
